UNITED STATES PATENT OFFICE.

EDWARD E. WAKEFIELD, OF PROVIDENCE, RHODE ISLAND, ASSIGNOR TO HALKYARD MANUFACTURING COMPANY, OF PROVIDENCE, RHODE ISLAND, A CORPORATION OF RHODE ISLAND.

LACING-STUD-SETTING MACHINE.

1,133,594.

Specification of Letters Patent. Patented Mar. 30, 1915.

Application filed October 24, 1914. Serial No. 868,850.

To all whom it may concern:

Be it known that I, EDWARD E. WAKEFIELD, a citizen of the United States, and resident of Providence, in the county of Providence and State of Rhode Island, have invented certain new and useful Improvements in Lacing-Stud-Setting Machines, of which the following is a specification.

This invention relates to improvements in machines for automatically setting lacing studs such as hooks or eyelets in shoe uppers, and is of the class adapted to feed a strip of reinforcing tape with the shoe upper to be connected to the latter by the setting of lacing studs thereinto.

This invention is an improvement on my co-pending application Serial No. 845,939.

The object of my present invention is to provide means whereby the feeding of the tape may be discontinued when desired to permit the upper to be fed without feeding the tape.

A further object of the invention is to provide means for locking the tape engaging means either in operative or inoperative position.

In some cases in the setting of studs into shoe uppers it is found desirable to pass the shank of the stud from the outside of the upper through the inner lining and rivet the same thereto, leaving the riveted or turned over portion of the stud exposed on the inner side of the upper. In other cases such as in the construction of some higher class shoes, what is known as blind setting is often desired, in which case a reinforcing strip must be laid against the inner surface of the upper to strengthen and support the same for the reception of the stud and after the setting of the stud the lining is positioned to cover the riveted portion and leave the upper smooth on the inner side. Therefore, it will be seen that a stud setting machine may be called upon to feed the tape for the blind setting operation or to feed the upper without the tape for the plain or exposed style of setting, therefore, to accomplish these results by a single machine I have provided mechanism adapted to engage the reinforcing tape when desired, or these engaging means may be readily withdrawn and locked in inoperative position so that the upper may be fed without the tape when desired.

With these and other objects in view, the

invention consists of certain novel features of construction, as will be more fully described, and particularly pointed out in the appended claims.

In the accompanying drawings: Figure 1— is a side elevation illustrating the portion of the mechanism for feeding the shoe upper, and means in the feeding means for engaging and feeding the reinforcing strip, said engaging means being in operative position. Fig. 2— is similar to Fig. 1 showing the strip feeding means as having been moved to inoperative position and the upper feeding means as having advanced without feeding the reinforcing strip. Fig. 3— is a section on line 3—3 of Fig. 2 also showing a portion of the feeding head. Fig. 4— is an enlarged sectional plan view on line 4—4 of Fig. 2 and the supporting block in which the tape engaging means is mounted. Fig. 5— is a view in perspective showing the tape engaging spurs and the mechanism for moving these spurs into and out of operative position. Fig. 6— is a perspective view of the toothed shaft for operating the tape engaging spurs. Fig. 7— is a section on line 7—7 of Fig. 6 showing the flattened or recessed portion of this shaft which receives the locking bolt by which it is held in operative or inoperative position. Fig. 8— is a perspective view of the locking bolt. Fig. 9— is a perspective view of one of the tape engaging spurs showing the teeth in the shank for engaging its operating shaft.

In my co-pending application above referred to I have described, and shown the mechanism to which my present improved mechanism is attached and by which it is operated. I have also set forth that the term "lacing stud" used throughout the specification and claims, refers to and includes both the eyelet and lacing hook formation ordinarily employed in shoe uppers, and the same is intended to apply with equal force to my present patent application.

I have herein shown and described only sufficient mechanism to illustrate my present invention.

In the accompanying drawings 10 designates a portion of the carriage in which is mounted the punch spindle 11 and the spring pressed foot spindle 12, the latter spindle being supported from the former by 110

the collars or guide blocks 13 and 14. In this spindle 11 is connected the punch 15 which forms holes in the tape 16 for the reception of the lacing studs 17, also on this spindle is mounted the cutter 26 for severing the reinforcing tape. The guide block 14 connected to the spindle 11 also serves to carry one or more needles or spurs 19, which are arranged to engage the tape for the purpose of causing it to advance with the feeding movement of the carriage head when desired which mechanism is fully described in my above mentioned co-pending patent application. The usual presser foot 20 which is raised and lowered by means (not shown) is provided with ways 22 in which slide the block 23. This block is also provided with vertical holes 27 through which the spurs pass on their way into and out of engagement with the reinforcing tape.

The essential feature of my present invention is the provision of means for adjusting or positioning the needles or spurs so that they may be caused to engage the strip of reinforcing tape, and place the same in position to be advanced simultaneously with such feeding movement of the shoe upper, for the purpose of positioning the tape to reinforce the upper about the studs when set therein when "blind hooking" is desired. This adjusting mechanism is also adapted to readily remove or withdraw the spurs to permit the upper to be fed without feeding the strip. To accomplish this result I have formed a shank 28 on these spurs which is adapted to slide vertically in the holes 29 in the guide block 14 and have provided each shank with teeth 30. I have also provided a spur operating shaft 31 whose body portion is toothed to engage those on the spur shank, this shaft is mounted in a longitudinal hole 33 in the guide block 14 so that its teeth will engage those of the spurs whereby the rotation of this shaft causes these spurs to receive a vertical adjustment. This shaft 31 is retained in position in its bearing by the screw 34 and washer 35. In some cases in the setting of these spurs either in their extreme up or extreme down position, it is advisable to lock them in each of these positions to positively prevent them from being inadvertently moved while the machine is operating. To accomplish this locking effect I have provided a locking bolt 36 adapted to be moved in the hole 37 which is at a right angle to the spur operating shaft, a spring 50 holding this bolt normally in out or locked position. This bolt is provided with a recess or cut away portion 38 on its under side which when moved to register with the shaft 31 permits the latter to rotate and operate the spurs. The notched portion of this shaft is provided with two recesses 39 and 40 set at right angles to each other, see Fig. 6, each

of which is adapted to receive the rounded or full portion 41 of the body of the bolt, the recess 39 being in position to receive the bolt when the spurs are in their extreme down position, and the recess 40 for receiving the bolt when the shaft has been rotated a quarter turn to move the spurs to their extreme up, or inoperative position. To limit the outward motion of this bolt I have cut away one side 42 of the same under the head 43 for the reception of the end of the stop screw 44, against which it brings up.

In operating this adjusting mechanism it is only necessary to press the bolt inward against the spring 50 bringing the recessed portion 38 over one or the other of these recesses 39 and 40 of the toothed shaft thereby releasing this shaft to be rotated by the hand of the operator to move the spurs from operative to inoperative position or vice versa, and upon releasing the bolt 36 it will move outward under action of the spring and its rounded portion 41 will engage the recess presented and securely lock the mechanism firmly in position against further movement in either direction.

The tape 16 is led from the reel (not shown) through a suitable guide 45 supported from the arm 46 in which guide a tension spring 47 is mounted to prevent the tape from receding or moving backward during the return stroke of the feeding mechanism. From this guide the tape is led through the aperture 24 in the guide block 23 above the engaging surface of the presser foot and over the cutting edge of the cutter plate 25 and severs the portions 48 of the tape which may be extending through the block 23. The downward movement of this spindle 11 also causes the punch 15 to engage and carry the severed portion of the tape down against the shoe upper or work 6 and to punch a hole through the tape and also through the work to receive the stud. The work is next advanced bringing the punched holes into position to receive the stud which is passed through said holes in both the upper and tape and riveted in position over the piece of tape as fully described in said co-pending application. After the stud has been set the spindle 11 is raised, withdrawing the spurs 19 and knife plate 18 from engagement with the tape and the head is then carried to the right back into position illustrated in Fig. 1 and this cycle of operations is repeated in the setting of each stud into the work. When the spurs are raised to inoperative position by the mechanism above described, the upper is fed without the tape and the studs set in the usual way ordinarily passing through both the upper and the lining over which they are riveted.

We have shown and described one form of mechanism for adjusting the spurs so that

they may be moved to operative or inoperative position at the will of the operator and locked in either position, but any means which may be used in conjunction with the feeding and cutting of the tape and connecting the same to the shoe upper to accomplish this adjustment of the tape engaging means will fall within the spirit and scope of my invention.

10 I claim:

1. In mechanism for applying lacing studs to shoe uppers, means for feeding an upper, means in said feeding means for feeding a reinforcing strip when desired, means for severing the strip and applying the severed sections to the upper when both are fed and means whereby said strip feeding means may be withdrawn to permit the uppers to be fed without feeding the strip.
2. In mechanism for applying lacing studs to shoe uppers, means for feeding an upper, means in said feeding means for feeding a reinforcing strip when desired, means for applying studs and also sections of said reinforcing strip when both are fed to said uppers, and means whereby the strip feeding means may be rendered inoperative when desired.
3. In mechanism for applying lacing studs to shoe uppers, means for feeding an upper, one or more spurs in said feeding means adapted to engage and feed a reinforcing strip; means for severing the strip and applying the severed section when fed to the upper, and means whereby said spurs may be withdrawn to permit the uppers to be fed without feeding the strip.
4. In mechanism for applying lacing studs

to shoe uppers, means for feeding an upper, one or more spurs in said feeding means adapted to engage and feed a reinforcing strip, means for severing the strip and applying the severed section when fed to the upper, means whereby said spurs may be withdrawn to permit the uppers to be fed without feeding the strip, and means for locking said spurs when in engaged or disengaged position.

5. In mechanism for applying lacing studs to shoe uppers, means for feeding an upper, one or more spurs carried by said feeding means for engaging a reinforcing strip during the feeding stroke to simultaneously advance said strip, means for severing the strip and applying the severed section when fed to the upper, and rack and pinion mechanism for moving said spurs to and from operative position.

6. In mechanism for applying lacing studs to shoe uppers, means for feeding an upper, one or more spurs carried by said feeding means for engaging a reinforcing strip during the feeding stroke to simultaneously advance said strip, means for severing the strip and applying the severed section when fed to the upper, rack and pinion mechanism for moving said spurs to and from operative position and means for locking said mechanism in the desired position.

In testimony whereof I affix my signature in presence of two witnesses.

E. E. WAKEFIELD.
